UNITED STATES PATENT OFFICE.

ALBERT McCARTHY, OF NEW ORLEANS, LOUISIANA, ASSIGNOR OF NINE-SIXTEENTHS TO HUBERT M. ANSLEY, W. H. FITZPATRICK, AND MARINA RUELLO, OF NEW ORLEANS, LOUISIANA.

EXCAVATING-MACHINE.

SPECIFICATION forming part of Letters Patent No. 769,105, dated August 30, 1904.

Application filed February 11, 1904. Serial No. 193,153. (No model.)

To all whom it may concern:

Be it known that I, ALBERT McCARTHY, a citizen of the United States, residing at New Orleans, in the parish of Orleans and State of Louisiana, have invented certain new and useful Improvements in Excavating-Machines; and I do hereby declare the following to be a full, clear, and exact description of the invention, such as will enable others skilled in the art to which it appertains to make and use the same.

My invention relates to improvements in excavating-machines, and is especially applicable for use as a ditching-machine for digging trenches for laying pipes, whereby the trench is automatically dug and the earth conveyed to a distant point in the trench to the rear of the machine for filling in the trench after the pipe has been laid.

The invention is primarily designed to comprise a plurality of transversely-disposed picks arranged in a series of vertical rows, forming an endless chain of digging implements, together with a plurality of transversely-disposed scoops or buckets similarly arranged to form an endless conveyer and located to the rear of the picks, the said picks and scoops being carried by a suitable movable support and adjustable vertically therefor for regulating the depth of the trench, suitable means being provided for gradually feeding said movable support along a track or otherwise.

Another object of my invention is to provide means whereby the said picks and scoops may be readily raised and lowered and held rigidly supported in their adjusted position for regulating the depth of the trench.

Other objects and advantages will be apparent, and the novel features of the invention will appear from the following description, and more particularly specified in the claims.

To more fully understand the invention, reference is had to the accompanying drawings, illustrating the same, in which like characters designate like parts in the several views, and in which—

Figure 1 represents a side elevation of my

improved ditching-machine; Fig. 2, a plan view of the same; Fig. 3, a front elevation of a portion of the endless chain of picks; Fig. 4, a sectional view of same on the line 4 4 of Fig. 3; Fig. 5, a side elevation of one of the pulleys over which the connecting-links for the picks and scoops reeve; Fig. 6, a sectional view therethrough on the line 6 6 of Fig. 5; Fig. 7, a front elevation of the endless conveyer means, showing one of the scoops in front elevation; Fig. 8, a section on the line 8 8 of Fig. 7; Fig. 9, a detached plan view of one of the scoops and the connecting-links; Fig. 10, a sectional view on the line 10 10 of Fig. 9; Fig. 11, a perspective detail view of a detached scoop looking toward the rear face thereof, and Fig. 12 a detail sectional plan on line 12 12 of Fig. 1.

A represents a suitable movable platform or base support.

B is an adjustable frame above said base-support, to which is suitably secured the depending side timbers C and D, forming a channeled guideway for the series of picks and scoops, respectively.

E represents rear upright bars connected to and forming a part of the support of the adjustable frame B. The upper end of the bars E extend above the top face of the adjustable frame B and are provided with the inwardly-extending arms or brackets E', in which are mounted the supports D', forming bearings 80 for a shaft D', carrying a plurality of transversely-disposed pulleys F. The projecting ends of the arm E' are supported forwardly by the side timbers D, which extend above the adjustable frame B. The lower end of the bars or supports E are provided with the braces or supports g, connected to the rear of a hopper G, the forward side faces of the hopper G being suitably secured to the lower end of the depending timbers C.

C' represents supports carried on the upper face of the adjustable frame B, forming bearings for a transversely-disposed shaft C', carrying a plurality of pulleys F, similar to the pulleys on the shaft D'.

The lower ends of the timbers C and D ex-

tend within the hopper G, which is simply a shell having side and rear walls, and are provided with the transverse shafts C³ D³, carrying a plurality of pulleys similar to and arranged in alinement with the pulleys F on the shafts C² D².

H is a rotary brush extending transversely across the hopper and journaled in the side walls thereof. The shaft of this brush H is 10 provided with a sprocket-wheel h, connected by a sprocket-chain H' to a similar sprocket-wheel h' on the shaft C³. The brush H is adapted to engage the series of picks as they ascend from the hopper for removing any 15 clinging soil and by the arrangement of the gearing is rotated in a direction the reverse of the movement of the ascending picks.

Referring more particularly to Figs. 3 to 6, I represents cross-bars provided on their front 20 face with a plurality of picks or downwardly-curved chilled points i, the picks of one bar being so disposed as to be a little out of alinement with the picks on the next adjacent bar. The rear face of these plates are provided 25 with a plurality of transversely-disposed channeled link members J, pivotally connected to similar members on the next adjacent bar I by the intermediate link member J', the channeled link members J and intermediate 30 members J' adapted to respectively engage during their continuous motion the tongues F' and slots F⁰, alternately disposed circumferentially around the pulleys F.

In Figs. 7 to 10 a substantially similar arrangement for supporting the scoops or buckets is shown, the cross-bar I' being carried by the channeled link members J², connected by the intermediate members J³. The scoops or buckets K are provided with the angle-plates 35 k, spaced sufficiently from the rear face of the scoops to snugly fit over the cross-bars I' and held thereon, although it is obvious that any other suitable securing means for the scoops may be provided. L represents a transversely-disposed pipe located adjacent the upper end 40 of the series of conveyer-buckets K, the said pipe being provided with a plurality of perforations l for directing a spray of water on the scoops or buckets as they rotate around 45 their upper supports, the object being to thoroughly clean the buckets as they begin to descend. This pipe L is connected to a suitable water-supplying means, such as the pump L', by means of the pipe connection l'.

55 In carrying out my invention I also provide suitable means for carrying off the contents of the scoops or buckets to a suitable distant point—for instance, back again into the trench for filling up the same after the pipe 60 has been laid—or to any other point. In the drawings I have illustrated this by means of the chute M, pivotally supported at its inner end, as at m, beneath the upper end of the series of buckets, and within this chute I may 65 provide an endless belt or apron N, reeving

over suitable rollers m' n', carried by the shafts m n. It is obvious that the length of this chute will be dependent upon the distance to which the dirt is to conveyed; but for simplicity of illustration I have simply shown it 70 as extending but a short distance to the rear of the machine. I also provide suitable means for elevating or lowering the adjustable frame B, carrying with it the series of picks and buckets for regulating the depth of the trench. 75 In the drawings I have illustrated this means as comprising a pair of derrick-arms P on each side of the machine, pivotally mounted to be moved in a vertical plane, as at p, in brackets P', pivotally secured, as at p', to the 80 movable support A. In their normal position these derrick-arms are held in a position, as indicated in Figs. 1 and 2, by means of the stay-ropes O, suitably secured at their respective ends to the frame B and the outer 85 ends of the derrick-arms. When the derrick-arms are thus held in their normal position, I have shown chute N as being supported by means of the hooks o, carried at one end of the cable O', passing through suitable eyelets 90 or pulleys p⁰ on the upper ends of the derrick-arms and reeving over pulleys o' on the adjustable support E and thence at their other ends, passing around a drum or windlass P², carried by the derrick-arms P. It is obvious, 95 however, that this arrangement might readily be modified under varying circumstances. When it is desired to raise or lower the adjustable frame B, carrying the series of picks and scoops, the derrick-arms are swung 100 around on their pivotal supports rearwardly and upwardly, when the hooks o are passed through the eyelets b⁰ on the cross-bar b of the adjustable frame B, and by operating the windlasses the frame may be raised or lowered 105 after having been unlocked from its supporting-base A.

Any suitable locking means may be provided for holding the frame B in its adjusted position. In the drawings I have illustrated the simple method of providing the timbers C and the uprights E with perforations c e, respectively adapted to register with similar perforations through the side beams A' of the movable support A, whereby the beams 110 C and uprights E may be held in any adjusted position relatively to the base-support A by means of the bolts or pins a, passing through the apertures in the supports A' C E.

Any suitable means may be provided for 120 feeding the movable support A forward during the operation of the machine. Also any suitable connection may be used for operating the picks, buckets, and endless conveyer-belt. For purposes of illustration I have 125 shown a pair of engines Q R and boiler Q', carried on the forward end of the platform A. The piston-rod and crank of the engine Q rotates the worm q and engages a worm-wheel q', carried by a drum q², around which is 130

wound a cable q^3 , connected at its free end with a stake or other stationary means forward of the machine. The piston and crank of the engine R are in operative connection 5 with a drum R', geared to a second drum R².

On the inner end of the shaft C² is mounted a drum c², and adjacent thereto on said shaft is a gear-wheel c³, meshing with a gear c⁴, carried by the shaft of a suitably-mounted drum 10 c⁵ adjacent the drum c². The shaft D² extends at its inner end some distance beyond its support and carries a drum d² and a sprocket-wheel d³, connected, by means of a sprocket-chain m⁰, to a sprocket-wheel m², carried on 15 the shaft m of the roller m'. The drums c⁵ and d² are operatively connected by means of the cable 1, and the drum c² is operatively connected with the driving-drums R' R² by means of the cable 2, which is wound around the 20 drum R², thence around the drum R', thence around the drum c², and back to the drum R², 2^a representing any suitable connection between the ends of the cable whereby the same may be shortened or lengthened when the 25 frame B⁰ is elevated or lowered.

3, 4, and 5 represent respective pipes connecting the boiler Q² with the cylinders of the engines Q, R and the pump L'.

In Fig. 12 I have shown in detail the means 30 whereby the buckets are guided along the timbers D. From this view, in connection with Fig. 1, it will be seen that the rear surface of the projecting ends i' of the cross-bars I engage and slide along the front and 35 rear faces of the timbers D, and similarly the rear faces of the corresponding projecting ends i² of the cross-bars I, carrying the picks, engage and slide along the front and rear faces of the timbers C.

40 In operation the shafts C², D², and m are operated from the drums R' R² by means of the cables 21 and sprocket-chain m⁰, thus rotating the pulleys F and operating the picks, scoops, and endless belt N, the rotation of the shaft 45 C² operating the brush H to clean the picks as they ascend from the hopper and the scoops or buckets K, scooping up the dirt, conveying it to the apron N. During the operation of the machine the engine Q drives the drum 50 q², winding the cable q³ thereon, thus gradually feeding the machine forward while the picks and shovels are in operation, thereby making the digging operation a continuous one.

55 It is obvious that many modifications might be made in the construction and arrangement of the various parts of the machine, and I wish it understood that I do not limit myself to the details as shown; but

60 What I claim is—

1. In an excavating-machine, the combination with a suitable movable support, of an endless flexible means rotatably carried by said movable support, transverse plates carried by 65 said flexible means, a plurality of picks affixed

to said transverse plates, a plurality of movable scoops located in the rear of said picks and carried by said movable support, and means for conjointly operating said flexible means and scoops and feeding said movable support forward during said operation. 70

2. In an excavating-machine, the combination with a suitable movable support, of endless flexible means rotatably carried by said movable support, transverse plates carried by 75 said flexible means, a plurality of picks affixed to said transverse plates, the picks on one plate being arranged out of alinement with the picks on the next succeeding plates, a plurality of movable scoops located adjacent said 80 series of picks and carried by said movable support, and means for conjointly operating said flexible means and scoops and feeding said movable support forward during said operation. 85

3. In an excavating-machine, the combination with a suitable movable support, of endless flexible means rotatably supported above and below said support, transverse plates carried by said flexible means, a plurality of picks 90 affixed to said transverse plates, a second flexible endless means rotatably supported above and below said support in the rear of said picks, a plurality of scoops carried by said second flexible means, and means for conjointly operating said picks and scoops and feeding said movable support forward during 95 said operation.

4. In an excavating-machine, the combination with a suitable movable support, of a series of endless flexible means rotatably supported above and below said support, a plurality of transversely-disposed plates carried by said series of flexible means and provided with picks thereon, a second series of endless 100 flexible means rotatably supported above and below said support in rear of said picks, a plurality of scoops carried by said second series of flexible means, and means for conjointly operating said flexible means and feeding said 105 movable support forward during said conjoint operation. 110

5. In an excavating-machine, the combination with a suitable movable support, of adjustable depending supports carried by said 115 movable support, endless flexible means rotatably supported adjacent said depending supports and adjustable therewith, transverse plates carried by said flexible means adapted to engage and be guided by said depending supports, a plurality of picks affixed to said transverse plates, a plurality of movable scoops located adjacent said picks and carried by said movable supports, and means for conjointly operating said flexible means and 120 scoops and feeding said movable support forward during said operation. 125

6. In an excavating-machine, the combination with a movable support, of a plurality of picks or cutters carried by said movable sup- 130

port, depending supports adjacent said picks or cutters, endless flexible means rotatably supported adjacent said depending support, transverse plates carried by said flexible means 5 adapted to engage and be guided in operation by said depending supports, scoops affixed to said transverse plates, and means for conjointly operating said picks and cutters and said flexible means and feeding said movable 10 support forward during said operation.

7. In an excavating-machine, the combination with a suitable movable support, of adjustable supports carried thereby and extending above and below same adjacent each other, 15 flexible means rotatably mounted adjacent each of said adjustable supports, a plurality of transverse plates carried by each of said flexible means and adapted to be engaged and be guided by said depending supports in their 20 substantially vertical movement, a plurality of picks carried by one set of said transverse bars, a plurality of scoops carried by the other set of said transverse bars, and means for conjointly operating said picks and scoops and 25 feeding said movable support forward during said conjoint operation.

8. In an excavating-machine, the combination with a suitable movable base-support, of a frame above and adjustable vertically of said 30 base-support, depending supports carried by said frame and extending below said base-support, rotary means journaled above and in the lower ends of said depending supports, endless flexible means carried by the forward set 35 of rotary means, a plurality of picks carried by said flexible means, endless flexible means carried by the rear set of said rotary means, scoops carried by said second flexible means, means for conjointly operating said flexible 40 means carrying said picks and scoops and moving said movable support forward during said conjoint operation, means for raising and lowering said adjustable frame, and means for locking said frame in its adjusted position.

45 9. In an excavating-machine, the combination with a series of suitably-supported movable picks, of a series of suitably-supported movable scoops located in the rear of said picks, a hopper inclosing the lower ends of 50 said series of picks and scoops, and means for conjointly operating said picks and scoops and feeding same and said hopper forward during said conjoint operation.

55 10. In an excavating-machine, the combination with a series of suitably-supported movable picks, of a series of suitably-supported movable scoops located in the rear of said

5 picks, a hopper inclosing the lower end of said series of picks and scoops, a rotary brush journaled in said hopper and engaging said 60 picks, means for rotating said brush, and means for conjointly operating said picks and scoops and feeding same and said hopper forward during said conjoint operation.

11. In an excavating-machine, the combination with a series of suitably-supported movable picks, of a series of suitably-supported movable scoops located in the rear of said picks, a transversely-disposed perforated pipe located at the upper end of said series of 70 scoops for directing sprays of water in the descending scoops at the top of the series, and conveying means located at the upper end of said series of scoops for receiving and carrying off the contents thereof. 75

12. In an excavating-machine, the combination with a suitable movable support, of an adjustable support carried by said movable support, excavating and conveying means carried by said adjustable support and means 80 for operating same, a derrick or gaffs carried by said movable support, and means operatively associated with said derrick or gaffs and said adjustable support, for raising or lowering the latter. 85

13. In an excavating-machine, the combination with a suitable movable support, of an adjustable upright support carried thereby, excavating and conveying means carried by said adjustable support and means for operating 90 same, a discharge-chute mounted on said adjustable support adjacent said conveying means, means for raising and lowering said adjustable support, and means for holding same in its adjusted position. 95

14. In an excavating-machine, the combination with a suitable support, of a vertically-adjustable support carried thereby, excavating and conveying means carried by said adjustable support and means for operating same, a discharge-chute pivotally mounted adjacent said conveying means, a derrick or gaffs mounted on said movable support, and means operatively associated with said derrick or gaffs for elevating or lowering said 100 adjustable support and supporting the free end of said pivoted discharge-chute. 105

In testimony whereof I affix my signature in presence of two witnesses.

ALBERT McCARTHY.
